FUSE PLUG

Louis Ludwig, Brooklyn, N. Y.

Application March 23, 1935, Serial No. 12,661

1 Claim. (Cl. 200—121)

My invention relates to fuse plugs of the type having an opening covered with transparent material through which the interior of the plug may be observed. The invention has for its main objects to provide simple means within such a fuse plug, immediately below the transparent opening, which will positively indicate whether or not the fuse is "blown". Another object is to provide positive means for assuring that the fusible link will always "blow" at a predetermined point. An additional object is to so construct these means that they will add but very slightly to the cost of the fuse plug.

These and various other objects and advantages will be readily understood from the following description and from the accompanying drawing, in which, however, various modifications may be made. In the drawing

Fig. 1 is a top view of a fuse constructed in accordance with my invention,

Fig. 2 is a cross-sectional side view of Fig. 1,

Fig. 3 is another, but fragmental cross-sectional view,

Fig. 4 is a disc used with the fuse,

Fig. 5 is a similar disc slightly modified,

Fig. 6 is a side view illustrating the manner in which either of the discs, shown in Figs. 4 and 5, are attached to the fusible link of the fuse.

Fig. 7 is another top view of the fuse with parts broken away to show certain details of construction, and

Fig. 8 a side view of Fig. 7.

I am aware that many indicating fuses have been invented in which a disc, or certain symbols imprinted on a disc, are caused to be destroyed or obliterated when the fuse is "blown". In some cases this has been accomplished by using a fusible powder in combination with the disc and in others by discoloring or imprinting the disc with some fusible material which will be discolored by the blowing of the fuse.

In other cases the gases and other products of combustion given off by the "blowing" of the fusible link has been relied upon to so disolor the disc as to indicate that the fuse has "blown". Repeatedly the "blowing" of such a fuse will fail to disolor the disc, either because the gases from the "blowing" of the fuse escaped too rapidly, or because the fusible link did not burn out on top of the disc as expected to. The time element is too short and there is not sufficient air in the closed chamber to always disolor the disc.

The purpose of the present invention is to remedy these defects. With this in mind, reference is now had to all the views on the drawing

on which the ordinary porcelain body of a fuse plug is shown at 10, the threaded metal ferrule at 11, the cap at 12, the opening in the cap through which the interior of the fuse may be observed at 13, the interior recess at 14, and the transparent mica disc which covers the opening at 15.

The invention consists in bringing the fusible metal strip 16 right up to or in very close proximity to, the mica disc and to place an insulating disc 17 under the exposed part of the fusible strip in such a manner that the smallest possible air pocket is formed between this disc and the mica disc. This I accomplished by slitting the disc in such a manner that two tongues 18 and 19 are formed substantially in the center of the disc so that, when the disc is bent, as shown in Fig. 6, these tongues may be placed on opposite sides of the exposed part of the fusible strip and closed under this strip when the disc is again straightened out by being clamped between the body member and the mica disc. This construction forms very small air pockets 20 on opposite sides of the fusible strip, while it causes the rest of the disc to contact with the mica disc. When the fusible strip "blows", the very close proximity to the mica of the point where it "blows" will cause the mica disc to become translucent, due to charring, and whatever gases are generated will disolor the indicating disc.

One end of the fusible metal is connected, in the usual manner, to the center contact 21 and the other end to the metal ferrule 11. The metal strip is weakened, at the exposed part, as shown at 22. The correct width of this weakened part is all important if assurance is to be had that the fusible strip will always "blow" at this point. Many prior fuses of this type have failed because the strip would often blow below the disc and not at the weakened part as anticipated.

I have discovered that to assure the certainty of the strip "blowing" at the weakened part, the width of this part must not be greater than .065 of one inch, (the gauge of the strip varying in thickness according to the load the fuse is to carry.) I have also found it advisable to make the weakened part comparatively long. In fact, I make it almost as long as the whole exposed part of the strip. With this construction, there is no danger, even with a "slow" overload on the fuse, that the strip will "blow" at any other place than within the pockets 20.

The disc 17 may be made of any non-conducting material and I have found that ordinary stiff paper will serve very well. The disc may be made

circular, as shown in Fig. 4 and of a size to fit within the cap 12, but I prefer to make it square or rectangular so that the corners 23 will be clamped down between the cap 12 and the body part 10. 5 Furthermore the square shape is cheaper to produce.

It will be noted that the two tongues form two shallow chambers one on each side of the exposed part of the fusible strip. If symbols, such 10 as for example an "O" and a "K", are imprinted, one on each of the tongues or in line with the tongues, it is evident that, when the fuse "blows", the chambers formed by the tongues will direct the gases so that they will flow over these symbols and obliterate them. 15

What actually takes place is that the gases soot and partially scorch the underside of the mica disc and the upper side of the paper disc. As this sootting and scorching takes place over and in line 20 with the tongues it is evident that the symbols are sure to be obscured. In other words, a sooted streak is formed across the mica disc which will show very plainly, even when the mica disc is quite dirty and dusty as it may be from long use. 25 The gases finally escape into the interior of the fuse through the opening of the tongues.

Figs. 7 and 8 illustrate the manner in which the fuse is vented so that the gases may escape from it without any fire hazard. The upper face 30 of the body member 10 is scored with a number of grooves at right angles to each other so as to form a plurality of raised points with a plurality of tortuous channels between them, as shown at 24. After the gases enter the interior chamber 14, they are free to escape through these tortuous channels, still, if the gases should be ignited, the flame will be extinguished before 35 it can pass through the channels.

The paper discs may be made in various colors 40 to indicate the capacity of the fuse or the capacity

may be imprinted on the disc, as shown in Figs. 4 and 5.

From the foregoing it will be seen that this construction contains the essential elements for assuring the correct operation of the fuse. The 5 shallow pockets not only prevent too rapid dissipation of the gases, but effectively direct them over the parts which are to be obscured. The tongues prevent excessive pressure on the mica disc, the correct weakening of the fusible link 10 assures it "blowing out" at the correct place, and the channels remove any danger of fire. Furthermore, the only addition to the ordinary fuse is the paper disc which can be manufactured at very low 15 cost and inserted without altering the ordinary assembling processes of the fuse.

Having described my invention and its objects, what I claim as new and wish to protect by Letters Patent is:

The combination with a fuse plug of the type 20 comprising a one-piece body member made of insulating material and having an interior recess covered with a transparent disc, a threaded metal shell secured on the outside and a metal contact secured in the bottom; of a fusible metal strip 25 contained in the recess and connecting the metal shell with the center contact and having a part bent up adjacent to the transparent disc, a disc of non-conducting material having two oppositely- 30 disposed tongues sheared substantially in its center, said disc foldable so that said tongues may be straddled over the fusible strip after this has been permanently secured in the recess and straightened again so as to place the tongues under said strip to form shallow pockets on both 35 sides thereof, said disc clamped between the end of the body member and the transparent disc, and the fusible strip having a weakened portion contained within said pockets.

LOUIS LUDWIG. 40
